UNITED STATES PATENT OFFICE.

SNOWDEN B. REDFIELD, OF EASTON, PENNSYLVANIA, ASSIGNOR TO INGERSOLL-RAND COMPANY, OF JERSEY CITY, NEW JERSEY, A CORPORATION OF NEW JERSEY.

COMPRESSOR UNLOADER.

Application filed May 16, 1923. Serial No. 639,269.

To all whom it may concern:

Be it known that I, SNOWDEN B. REDFIELD, a citizen of the United States, a resident of Easton, county of Northampton, 5 and State of Pennsylvania, have invented a certain Compressor Unloader, of which the following is a specification accompanied by drawings.

This invention relates to compressor unloaders, but more particularly to an unloader for relieving the fluid compression load, during the period of starting. The compressor may be operated for instance, by an electric motor, automatically started 10 and stopped by means of an automatic pressure controlled electric switch, but my unloader preferably has no connection with the control switch, and the unloading operation is performed only by the action of 15 the compressor itself.

The objects of the present invention are to produce an improved means for positively controlling the starting period of the compressor, so that the load will not be 20 thrown on the compressor until a predetermined speed of the compressor piston has been reached, and for permitting the pressure on both sides of the compressor piston to be relieved as the compressor stops.

To these and other ends, which will hereinafter appear, the invention consists of the apparatus shown in one of its preferred forms in the accompanying drawings, in which —

Figure 1 is a vertical sectional view of a compressor unit, with the unloader and pilot valves connected thereto showing the position the parts assume when the compressor is under load.

Figure 2 is an enlarged detail view partly in vertical section of the choking needle valve,

Figure 3 is a view similar to Figure 1 showing the position the parts assume when the compressor is starting or stopping, and the compressor piston is moving to the left, and

Figure 4 is a view similar to Figure 3 showing the position the parts assume when the compressor is starting or stopping and the compressor piston is moving to the right.

Referring to the drawings, the unloader A is connected to the discharge line B of a 50 compressor C between the compressor and

the usual receiver D. The compressor comprises the cylinder E having the reciprocating piston F adapted to be driven by any suitable source of power, as an electric motor (not shown). The compressor is provided with the inlet valves G, the discharge valves H, and the discharge chamber J, connected to the discharge line B.

The unloader comprises the valve casing K having the main valve chamber L separated from the outlet O by a partition P on which the main check valve Q is adapted to be seated for controlling the discharge from the casing. The check valve Q is provided with the spring R bearing on the valve and held by the cap S, which cap also forms a valve guide. The pressure in the receiver tank D normally holds the main check valve Q to its seat when the compressor is idle.

The wall T of the casing K is provided with a valve seat U on which a relief valve V is adapted to be seated for controlling communication between the main valve chamber L and atmospheric vent X, conveniently located in the side of the extension Y of the main casing K, in which the relief valve V operates. The relief valve V is preferably carried by a piston Z and has limited longitudinal movement relatively to the piston, being urged outwardly from the piston Z by a comparatively heavy coil spring a in the valve socket b, of sufficient strength to resist the full line pressure in the main valve chamber L and prevent the relief valve from opening from its seat U against the spring. The valve is held to its seat by the combined spring pressure and fluid pressure behind the piston Z. The movement of the relief valve V is limited by the pin c passing through the transverse aperture d in the valve, and secured at each end in the piston Z.

The piston Z is of the differential type and is provided with an enlarged head e forming a pressure area, when in its inward position, materially greater than the opposed pressure area on the face of the relief valve V, and pressure behind the piston head e will force the relief valve V to its seat U with sufficient force to compress the strong spring a and also hold the piston head e firmly against the seat f in the extension y of the casing, so that leakage of fluid past the piston from behind the piston

head is shut off and prevented. The relative longitudinal movement or lost motion connection provided between the relief valve V and the piston Z enables both the valve 5 and the piston to be tightly seated on their seats U and f respectively.

A projection or stop g on the piston Z is adapted to bear against an adjusting screw h in the cap W by means of which the initial starting position of the piston Z and relief valve V may be adjusted.

The unloader so far described prevents the fluid compressing load from coming upon the machine until the motor is up to full speed. During the starting period fluid, as air, enters the main valve casing K at the inlet side and leaves at the atmospheric vent X, and the main check valve Q holds back the air in the receiver D and pipe lines. 20 When the compressor is started, the slight pressure built up in the main valve chamber L will force both the relief valve V and piston Z outwardly and substantially all the air will pass through the vent X to atmosphere. It is to be assumed that the adjusting screw h has been set at such a point that the relief valve and piston move rearwardly and open the relief valve the required amount, so that when the compressor is up 25 to full speed, there will be a throttling pressure of a few pounds as the air passes the relief valve V.

The loading should be delayed until substantially full compressor speed is reached, 30 and the unloading should occur automatically just as or before the compressor stops entirely. In order to make the unloader A operate positively on starting and to relieve the pressure on both sides of the compressor 35 piston F as the compressor stops, I provide a plurality of pilot valves, which are connected to the compressor cylinder and "in series" with the unloader.

In this instance, the pilot valves A' and 40 B' are connected by pipes y to the compressor cylinder adjacent each end thereof. A pipe or tube j connects the extension Y of the valve casing rearwardly of the piston Z with the port k in the upper section of the pilot valve B' in order to admit pressure fluid to or relieve it from the rear of the piston Z, as required. The pilot valve A' is in communication with the main valve chamber L through the pipe or tube o. As 45 shown in Figure 2, a choking needle valve p chokes or throttles the flow of pressure fluid from the main valve chamber L through the tube o, and may be adjusted to delay the loading point. A lock nut q holds the needle valve in a set position. A tube r affords communication between the two pilot 50 valves, and is connected to the top of the pilot valve B' and to the port k' in the pilot valve A'. The unloader and pilot valves 55 are connected "in series" and the advantage

of such a connection is that the pressure in the compressor cylinder on both sides of the piston is relieved on stopping, and the load is not thrown on the compressor on starting until the predetermined speed has been 70 reached.

The pilot valves A' and B' are identical in their construction, and each is composed of an upper section x' and a lower section x, held together in any suitable manner, as by 75 bolts and nuts. A downwardly seating ball check valve s is adapted to be moved to its seat t by a coiled spring u and controls the flow of pressure fluid through the upper casing section x'. An upwardly seating ball 80 check valve v spaced from the ball check valve s by the spacer pin 7 is adapted to be moved to its seat w by a plunger z to control the passage of pressure fluid to atmosphere through the port or vent 8.

The plunger z has limited movement in the piston 2 over a pin 3 passing through the transverse aperture 4 in the plunger. The ends of the pin 3 are secured in the piston 2. A comparatively heavy coiled spring 5 90 urges the plunger z forwardly, so that when the piston 2 is moved to its seat 6 in the casing x', the plunger z will move the ball valve v to its seat w. When the ball valve v is moved to its seat w, the ball valve s is accordingly moved from its seat t by the spacer pin 7. Thus, when one of the ball valves is seated, the other is unseated.

The check valve 9 having a small port 10 therethrough, controls the outlet of pressure fluid from the lower casing section x to the compressor cylinder. A coil spring 11 serves as a distance piece for the check valve 9, so that the valve will not be moved too great a distance from its seat.

When the compressor starts or stops, and the compressor piston is moving to the left, as shown in Figure 3 of the drawings, the pressure fluid from the compressor cylinder moves the piston 2 of the pilot valve A' upwardly to seat the check valve v, and by means of the spacer pin 7 unseats the check valve s. Pressure fluid may then pass from the main valve chamber L through the pipe or tube o into the pilot valve A', past the check valve s and spacer pin 7, and to the pilot valve B' through the pipe or tube r. As the compressor piston F is on its suction stroke, relative to the pilot valve B', pressure fluid passes from the lower section 110 x of the pilot valve B' to the compressor cylinder through the pipe y. The piston 2 in the pilot valve B' is moved downwardly by the action of the coil spring u, and entrance of atmospheric air through the port 8 in the casing section x'. The check valve s is seated at the same time by the coil spring u, thereby shutting off the passage of pressure fluid from the valve chamber L. The check valve v is accordingly unseated, so 125 130

that the passage through the pipe or tube *j* is opened to atmosphere through the vent *s* in the pilot valve casing *B'*.

When the compressor piston is moving to the right on starting or stopping, as shown in Figure 4, the operation of the pilot valves *A'* and *B'* just described is reversed. In this instance, the pressure fluid behind the piston *Z* in the extension *Y* of the discharge valve casing passes to atmosphere through the vent *s* in the pilot valve *A'*. The check valve *v* in the pilot valve *B'* is seated by the piston *2*, which is moved upwardly by pressure fluid admitted from the compressor cylinder into the casing section *x*, and closes the atmospheric vent *s*. The check valve *s* is unseated at the same time, and fluid is permitted to pass through the pipe or tube *r* to the pilot valve *A'* to be vented to atmosphere through the port *s* in the casing section *x'*. In either direction the compressor piston *F* moves on starting and stopping, a differential pressure is created in the compressor cylinder, and by means of the pilot valves, connected "in series," the pressure fluid behind the unloader piston *Z* is vented to atmosphere, and passage of fluid from the main valve chamber *L* to the piston *Z* is shut off and prevented.

During the time that the compressor is accelerating, the alternate rising and falling of the pistons *2* in both pilot valves will continue until the compressor piston *F* has attained such a speed that there is insufficient time during the suction stroke of the piston *F*, relative to each pilot valve alternately, for the pressure fluid in the spaces under the pistons *2* in each pilot valve *A'* and *B'* to escape through ports *10* in the check valves *9* to the compressor cylinder. When this condition has been reached, the pressure in the space under the pistons *2* in each pilot valve will be sufficient to hold the pistons *2* in each pilot valve in the extreme upward position throughout the normal running period of the compressor. When the pistons *2* are in the upward position, the check valves *v* in each pilot valve are seated and check valves *s* in each pilot valve are unseated. This allows pressure fluid to flow from the main valve chamber *L* through the pipe or tube *o*, past the check valve *s* and spacer pin *7* in the pilot valve *A'*, through the side outlet *K'* to the pipe or tube *r*, past the check valve *s* and spacer pin *7* in the pilot valve *B'*, through the port *k*, through the pipe or tube *j* to the extension *Y* of the main valve casing. The pressure fluid forces the piston *Z* inwardly, and moves the relief valve *V* to its seat *U*, thus shutting off the flow of air from the main valve chamber *L* through atmospheric vent *X*. Further increase of pressure back of the piston *Z* compresses the spring *a*, moving the enlarged head *e* of the piston *Z* to its

seat *f*, thereby sealing both relief valve *V* at its seat *U* and the piston *Z* at its seat *f*. The relief valve *V* being thus closed, pressure fluid from the compressor passes into the main valve chamber *L* increases the pressure therein to such a point as to overcome the spring *R* and fluid pressure in the discharge pipe *O* and receiver *D*. The check valve *Q* is then raised and pressure fluid is discharged from the compressor into the discharge pipe *O* and the receiver *D*, thus performing useful work. Further delay in the closing of relief valve *V*, in order to allow the compressor to attain higher speed before taking up its load, is secured by screwing in on the choking needle valve *p* as shown in Figure 2.

On stopping of the compressor during the slowing down of the piston *F*, sufficient time will be allowed on the suction strokes relative to each pilot valve, to allow the air under the pistons *2* to be discharged through port *10* in the check valves *9*. This will allow the pistons *2* to move down to unseat the check valve *v*, and reseat the check valve *s*. This action takes place alternately in the two pilot valves on alternate suction strokes. The unseating of the check valves *v* allows the pressure fluid from behind the piston *Z* to be discharged through the pipe or tube *j* to atmosphere through the vents *s* in the two pilot valves alternately with each suction stroke, and at the same time shuts off the passage of pressure fluid from the main valve chamber *L* by the alternate closing of check valves *s* in the two pilot valves. This is substantially the same action as was described for the starting period of the compressor.

The unloader should be adjusted to unload as promptly as possible on stopping. To this end, washers *13* are provided in the lower sections of the pilot valves, by which the volume under the pistons *2* may be varied. With high pressures, there is too great a volume of air under the pilot valve pistons *2* to permit quick passage thereof through the small port *10* in the check valves *9*, for the compressor to unload on stopping. It is therefore necessary to remove the lower section of the pilot valve casings and insert a greater number of washers *13* therein in order to reduce the volume into which pressure fluid may enter. On the other hand, with low pressure, it is necessary to increase the volume in the lower section of the pilot valve to prevent unloading during the running period, and to delay unloading while slowing down. To do this, the number of washers is reduced. A screw *14* is threaded into the upper section of the pilot valves, and extends into the external circumferential groove *15* in the pistons *2*, and serves to prevent the parts from falling out when the lower section of the

1 pilot valve is removed for adding to or removing washers from the lower section.

6 By means of the pilot valves and un-
loader, connected together "in series," all the
pressure fluid remaining in the compressor
cylinder, when the compressor stops, passes
10 to atmosphere through the vent X in the
extension Y of the main discharge valve
casing, thereby relieving the compressor
from load, until it has again attained sub-
stantially full speed.

I claim:

1. The combination with an unloader
15 adapted to be connected to the discharge
line of a compressor, of a plurality of pilot
valves connected in series with the unloader
and connected to the compressor cylinder
adjacent each end thereof, whereby pres-
20 sure on both sides of the compressor piston
is relieved on stopping.

2. The combination with an unloader
adapted to be connected to the discharge
line of a compressor, of a plurality of pilot
valves connected in series with the unloader
25 and connected to the compressor cylinder
adjacent each end thereof, whereby the com-
pressor remains unloaded until a predeter-
mined speed has been reached.

3. The combination with an unloader
30 adapted to be connected to the discharge
line of a compressor, of a plurality of pilot
valves connected in series with the unloader
and connected to the compressor cylinder
adjacent each end thereof, and means for
35 varying the time of unloading, whereby pres-
sure on both sides of the compressor piston
is relieved on stopping.

4. The combination with an unloader
40 adapted to be connected to the discharge
line of a compressor, of a plurality of pilot
valves connected in series with the unloader,
and a piston in each pilot valve, controlled
by the pressure in the compressor cylinder
45 and means for controlling the amount of
fluid admitted to the pistons.

5. The combination with an unloader
50 adapted to be connected to the discharge
line of a compressor, of a plurality of pilot
valves connected in series with the unloader,
a check valve in each pilot valve controlling
an atmospheric vent, and a piston for seat-
55 ing said check valve, controlled by the pres-
sure in the compressor cylinder.

6. The combination with an unloader
55 adapted to be connected to the discharge
line of a compressor, of a plurality of pilot
valves for operating said unloader and con-
nected in series therewith, comprising a cas-
ting, and check valves in the casing actuated
60 in one direction by the pressure in the com-
pressor cylinder, whereby unloading of the
compressor is controlled by the speed of the
compressor piston, and the compressor re-
mains unloaded until a predetermined speed
65 has been reached.

7. The combination with an unloader
adapted to be connected to the discharge
line of a compressor, a piston in the un-
loader, of a plurality of pilot valves con-
70 trolling the movement of said piston, and
connected in series with the unloader, and
means associated with the pilot valves for
varying the time of unloading, whereby the
pressure on both sides of the compressor
75 piston is relieved on stopping, and the com-
pressor remains unloaded until a predeter-
mined speed has been reached.

8. The combination with an unloader
adapted to be connected to the discharge
80 line of a compressor, of a plurality of pilot
valves connected in series with the unloader,
a plurality of check valves associated with
the pilot valves and means controlled by the
pressure in the compressor cylinder for seat-
85 ing and unseating said valves, whereby the
pressure on both sides of the piston is re-
lieved on stopping, and the compressor re-
mains unloaded until a predetermined speed
has been reached.

9. The combination with an unloader
90 adapted to be connected to the discharge
line of a compressor, and a valve in the un-
loader controlling an atmospheric vent, of
a plurality of pilot valves connected in
95 series with the unloader, and means associat-
ed with said pilot valves for varying the
time of unloading, whereby the pressure on
both sides of the piston is relieved on stop-
ping, and the compressor remains unloaded
100 until a predetermined speed has been
reached.

10. In combination, an unloader adapted
to be connected to the discharge line of a
compressor, comprising a valve casing hav-
105 ing a main valve chamber, a main discharge
valve controlling the outlet from said cham-
ber to the discharge line, a vent to atmos-
phere from said chamber, an automatic re-
lief valve controlling the vent to atmosphere
110 and actuated both to open and close by fluid
pressure, thereby preventing the opening of
the main discharge valve until the com-
pressor has attained sufficient speed to per-
mit the load to be safely thrown on the com-
pressor, and pilot valves connected in series
115 with the unloader, whereby pressure on both
side of the compressor piston is relieved on
stopping.

11. In combination, an unloader adapted
120 to be located in the discharge line of a com-
pressor, comprising a main valve casing, a
main discharge valve controlling the outlet
from said casing to the discharge line, an ex-
tension on the main valve casing, a vent to at-
mosphere from said extension, an automatic
125 relief valve controlling the vent to atmosphere
and actuated to both open and close by fluid
pressure, thereby preventing the opening of
the main discharge valve until the com-
pressor has attained sufficient speed to per-
130

mit the load to be safely thrown on the compressor, and pilot valves connected in series with the unloader and to the compressor cylinder adjacent each end thereof, check valves associated with said pilot valves, and means for seating one of said check valves controlled by the pressure in the compressor cylinder.

12. In combination, an unloader adapted to be connected to the discharge line of a compressor, comprising a main valve casing, a main discharge valve controlling the outlet from said casing to the discharge line, an extension on the main valve casing, a valve in said extension controlling a vent to atmosphere, and pilot valves connected in

series with the unloader and the compressor cylinder adjacent each end thereof, each of said pilot valves comprising a casing, a plurality of check valves in the casing, means controlled by the pressure in the compressor cylinder for seating one of said valves, said valves being so arranged that when one is seated the other is unseated, and means for varying the time of unloading, whereby the pressure on both sides of the piston is automatically relieved on stopping, and the compressor remains unloaded until a predetermined speed has been reached.

In testimony whereof I have signed this specification.

SNOWDEN B. REDFIELD.
